BISCUIT CUTTER

Dovie A. Owens and Myrtle K. Owens, Fulton, Miss.

Application August 25, 1953, Serial No. 26,581

Term of patent 7 years

(Cl. D44—1)

Fig. 1.

Fig. 2.

Fig. 3.

To all whom it may concern:

Be it known that we, Dovie A. Owens and Myrtle K. Owens, citizens of the United States of America, residing at Fulton, in the county of Itawamba and State of Mississippi, have invented a new, original, and ornamental Design for a Biscuit Cutter, of which the following is a specification, reference being had to the accompanying drawings, forming a part thereof.

Figure 1 is a side elevational view of a biscuit cutter showing our new design.

Figure 2 is a top plan view thereof; and,
Figure 3 is a bottom plan view thereof.

We claim:

The ornamental design for a biscuit cutter, as shown.
